UNITED STATES PATENT OFFICE

2,104,610

ANTENNA AND COUPLER SYSTEM

Robert B. Dome, Bridgeport, Conn., assignor to
General Electric Company, a corporation of
New York

Application December 24, 1934, Serial No. 758,917

9 Claims. (Cl. 250—33)

5 My invention relates to antenna and antenna coupling systems for radio receiver and transmitter apparatus, and its special object is to provide an antenna and coupler system such that transfer of radiant energy may be effected with improved efficiency by the antenna and coupler system over a wide range of wave bands.

10 The problem of providing a satisfactory antenna for use in conjunction, for example, with all-wave radio receivers to cover a wide frequency band is difficult of solution where it is desired to have no separate antenna tuning equipment, or antenna adjustment on the receiver.

15 Desirable characteristics of an antenna for such use include the following: The antenna should not require a separate adjustment on the receiver, or at an external unit; the signal level provided by the antenna should be uniform over the desired range of frequency; the signal level provided by the antenna should be as high as possible; the antenna should be designed to be free of pickup of local noise currents; the antenna should not be limited in its application by restricting either the lead-in length, the height, or the antenna length 20 to a rigid figure; the antenna should be simple in construction.

25 A difficulty in solving the problems involved in providing a suitable antenna for all-wave radio apparatus resides in the fact that the impedance of an antenna ordinarily varies over wide limits 30 periodically with frequency in a non-linear and practically discontinuous manner. Therefore simple tuned circuits which are fixed in tuning cannot satisfactorily tune the antenna over the entire range of wave bands. The solution of this latter problem would be to provide if possible an antenna which is not characterized by wide variations in impedance over the frequency range. This result could be obtained by making the antenna system short physically so that the length 35 of one feeder wire out to the end of the antenna wire would always be less than half a wave length. Such an arrangement, however, would call for an antenna system so short, as required for use with the highest frequency band, that its efficiency 40 over the lower frequency bands would be quite low. My present invention provides for the use of an antenna system which is longer physically and therefore much more efficient in the low frequency bands than the short antenna system 45 above noted.

50 In order to provide an antenna which, in connection with means for coupling the antenna to a radio apparatus circuit such as an input circuit of a radio receiver, has the desirable characteris-

tics hereinabove set forth, I have utilized a non-uniform transmission line as a feeder for, or a constituent part of the antenna system. Such a non-uniform transmission line may be, for example, a line which is characterized by an ever increasing elementary inductance and a fixed elementary capacity. The effect produced by a transmission line of this character can be estimated and approximately solved by dividing up the line into small finite sections, each section 5 having fixed elementary inductances and capacities; ordinary transmission line equations may then be applied to the sections in succession. Applying this method of solution to the non-uniform transmission line used for antenna purposes 10 I have discovered that the wave-length or reactance curve along such a non-uniform transmission line is materially longer than that along a uniform line. This means that the frequency range over which the antenna system including 15 such a non-uniform transmission line may be used before the half-wave resonance point of the reactance curve is reached is considerably extended, the system therefore covering efficiently a 20 wide range of wave bands.

25 The antenna system in accordance with my invention comprising the non-uniform transmission line may be considered as of the single doublet type, two oppositely extending conductors being continuations of, or connected to, or merging 30 into a pair of converging conductors. The converging conductors, at their inner ends, may be continued by, or connected to, a pair of conductors arranged closely adjacent throughout their length, for example a twisted pair of conductors. 35 In order that a highly efficient transfer of energy may be obtained in all directions perpendicular to, or broadside to the antenna conductors, the rate at which the transmission line conductors 40 diverge from the apex of the opening is preferably relatively rapid, this rate of divergence being such that energy transfer in the above-noted directions perpendicular to, or broadside to the conductors is substantially as great as in the 45 direction of the axis. The antenna in accordance with my invention is therefore substantially bi-directional.

50 Preferably the antenna comprising the non-uniform transmission line is arranged as a vertical antenna, the axis, or line bisecting the opening formed by the diverging pair of conductors being substantially vertical. However, the antenna under certain conditions may be arranged as a horizontal antenna, the axis or line bisecting 55

the opening of the conductors being then substantially horizontal.

My antenna system including the coupling means therefor is intended not only for use with 5 radio receivers or transmitters over a wide range of relatively high frequencies but also for use with radio apparatus, particularly radio receivers, over relatively low frequencies, such as comprised in the present United States broadcasting band. 10 A feature of my invention is therefore a coupling means for so connecting the antenna to a radio device such as a receiver that the antenna operates over the high frequency range of wave bands as a doublet including a noise-reducing system, 15 substantially all of the pick-up of energy being due to the antenna proper and little or none being due to the lead-in or twisted pair; and that the entire antenna system including the lead-in operates as a simple antenna over the low frequency 20 or broadcasting band and on other adjacent relatively low frequency bands if desired. It is a further feature of my invention that in its preferred form the coupling means is so arranged that the change of the antenna system from doublet, 25 noise-reducing operation on the high frequency bands to simple antenna operation on the relatively low frequency bands is effected automatically.

My invention will be better understood from 30 the following description when considered in connection with the accompanying drawing and its scope will be pointed out in the appended claims.

Referring to the drawing, Fig. 1 is a diagrammatic representation of a radio apparatus embodying my invention; Fig. 2 is a diagrammatic representation of one form of a coupling means between an antenna and a radio device; Fig. 3 is a diagrammatic representation of a coupling means including automatic means for changing 40 from doublet operation to simple antenna operation; and Fig. 4 represents curves indicating graphically the reactance at varying frequency for uniform and non-uniform transmission lines respectively.

45 In Fig. 1 the numeral 10 indicates a radio device which in the present embodiment of the invention is represented as a portion of a radio receiver of the all-wave type comprising a plurality of input circuits as 11, 12—which may be connected, in the usual manner as required for the reception of different wave bands, to input terminals 13, 14 through a suitable switch means 15. Since the radio receiver or similar radio device per se forms no part of the present invention it will not be described further herein.

In order to supply radio signals to the radio receiver device 10 an antenna system designated generally by the numeral 16 is provided, adapted to be coupled to the selected one of the input 60 circuits 11, 12—by a coupling means, designated generally by the numeral 17, which will be more fully described hereinafter. The antenna system 16 comprises open end portions 18, 19 extending or diverging in opposite directions and 65 gradually converging at their inner ends into a non-uniform transmission line. The wire portions 18, 19 may be merely divergent as shown for example in Fig. 1, or they may be in line, pointing 180° away from each other in substantially 70 the same position as usual doublet antenna wires. The non-uniform transmission line portion of the antenna system further includes the pair of conductor portions 20, 21 diverging from the apex point 22 of the opening 23 formed 75 therebetween at a relatively rapid rate and con-

tinuing to flare out to join the portions 18, 19. The portions 20, 21 may diverge smoothly as shown, or the divergence may be accomplished in a series of straight steps thereby lessening the number of guys or stays required to maintain the antenna in the desired form. The non-uniform transmission line portion of the antenna merges into a lead-in 24 constituted by a pair of conductors 25, 26 which are closely adjacent throughout their length and are preferably arranged, as shown in Fig. 1, as a twisted pair.

Referring to the coupling means hereinbefore mentioned for connecting the antenna system to the radio device, the form of this coupling means shown in Fig. 2 and designated generally by the numeral 27 comprises a coupling coil 28, a mid-tap 29 which may be connected to one input terminal, as the grounded terminal 14 of the radio device, or to ground, one extremity 30 of coil 28 being connected to another terminal 13 of the radio device. The lead-in conductors 25, 26 are connected respectively to the ends of coil 28. In order to prevent pick-up at high frequencies by the lead-in 24 the two halves 31, 32 of coil 28 are closely coupled. The 25 mid-tapped coil 28 of Fig. 2 is, however, preferably replaced by a coil 34 arranged, as shown in Figs. 1 and 3, as a step-up autotransformer having two taps 35 and 36, tap 36 being a mid-tap between tap 35 and one end 37 of coil 34. The 30 lead-in conductors 25, 26 are connected respectively to tap 35 and coil end 37. The mid-tap 36 may be placed in electrical connection with one input terminal, as the grounded terminal 14 of the radio device, or to ground, and the other 35 extremity 38 of coil 34 may be connected to another input terminal 13 of the radio device.

In order to change from doublet operation to simple antenna operation the tap 29 of Fig. 2, or the tap 36 of Figs. 1 and 3, may be simply disconnected from ground, this manual shifting from doublet operation to simple antenna operation being facilitated if desired by means of a switch, such as switch 39 shown in Figs. 1 and 2 in the lead between tap 29 or 36 and radio receiver terminal 14, and ground.

The shift between doublet and simple antenna operation is, however, preferably accomplished, in accordance with my invention, by the means illustrated in connection with Fig. 3. In order 50 to avoid the necessity of manual operation of a switch or other means, and to eliminate such switch or other mechanically operating means for shifting between doublet and simple antenna operation, I provide a capacitance means, illustrated as a condenser 40, providing such capacity that the shift between doublet and simple antenna operation is accomplished automatically.

Referring to the operation of the antenna system 16 illustrated in Fig. 1 it will be understood that since the antenna system, from its outer, wide open, flared portion, gradually converges into a transmission line, the system has the characteristics of a non-uniform transmission line, and the surge impedance of the system 65 therefore diminishes as the line approaches the radio receiver 10. For example, the outer portion of the antenna proper may have a surge impedance of 500 ohms, but that part of the antenna system finally connected to the radio receiver may have a surge impedance of but 90 ohms. The tapered transmission line therefore operates somewhat as a transformer tending to lower the relatively high impedances, out on the antenna, to moderate values of impedance which 70 75

are more suitable for the receiver input circuit. The manner in which the tapered transmission line, characterizing the antenna system shown in Fig. 1, operates to increase the frequency range over which the system may be used before the half-wave resonance point of the reactance curve is reached, will be better understood from Fig. 4. In the latter figure the curve 41 illustrates the usual reactance curve for a uniform transmission line, or line in which the impedance is substantially constant throughout, the curve 41 comprising a succession of half-wave resonance points 42 spaced relatively closely together along a desired wave band. The curve 43, however, illustrates the reactance curve for a non-uniform transmission line, such as hereinbefore described, of the same length physically as the uniform line whose reactance curve is illustrated as curve 41. For the given frequency range it will be seen as indicated by curve 43 that, in the case of the non-uniform transmission line, a far greater frequency range is passed over before a half-wave resonance point, 44 of curve 43, is reached than in the case of the uniform line. The incorporation in the antenna system 16 of the non-uniform transmission line therefore ensures, for an antenna which is physically of the single doublet type, efficient pick-up of radio signals over relatively broad ranges of high frequency wave bands.

Since the rate of divergence of the pairs of conductors 20, 21 from the apex 22 of the opening 23 between these flaring conductors, which are continued to form the portions 18 and 19, is relatively rapid, a highly efficient transfer of radio energy by the antenna occurs in all directions substantially perpendicular to the line formed by the finally expanded antenna wires. The antenna system 16 is therefore essentially bi-directional.

The antenna structure 16 is preferably mounted as a vertical antenna as shown in Fig. 1. It is to be understood, however, that under some conditions, as in case the antenna is located on the roof of a building, the antenna system may be mounted if desired with the axis 45 substantially horizontal. The oppositely extending portions 18 and 19 are shown in Fig. 1 as being of the same order of length as the distance between the points 46 and 47 which mark approximately the points of merging of the end portions 18, 19 into converging portions 20, 21. However, to suit the length of span to a given location the spread of the antenna may be reduced, with some corresponding loss of pick-up, by reducing the length of the portions 18, 19. I have found, further, that in order to make the antenna system less unwieldy in erection, the distance between the points 46 and 47 may be about one-half the length of the oppositely extending portion 18 or 19. The distance between the points 46 and 47 may be of the same order of magnitude as the distance between the apex point 22 and a line joining the points 46, 47. The length of the lead-in 24 is not critical, but a reasonably short lead-in should be used since the use of long lengths of uniform transmission line, such as the lead-in 24, near the radio receiver brings the half-way point down in frequency.

In operation of the coupling means which is combined with the antenna system 16 to form an antenna unit capable of attachment to existing radio receivers, during operation of the apparatus on high frequency wave bands any currents picked up by the lead-in conductors will enter the coil 28 of Fig. 2 for example, or the coil 48 of auto transformer coil 34 of Fig. 1, from op-

posite ends of coil 28 or 48 and will thence pass to ground through the mid-tap 29 of Fig. 2 or 36 of Fig. 1, the mid-tap 29 or 36 being connected directly to ground, or to ground through switch 39 which is closed for this purpose. Since the two halves of the coil 28 or 48 are closely coupled, no voltage will be set up between points 30 and 29 of coil 28 or points 35 and 36 of coil 48. Therefore no voltage which is due to noise currents picked up by the twisted pair lead-in conductors 24 will be transmitted from coil 28 of Fig. 2, or autotransformer 34 of Fig. 1, to the input circuit, as circuit 11 of the radio receiver 10.

However, the rest of the antenna system 16 will operate in the usual manner as a doublet antenna, any radio signals picked up by this doublet portion entering the coil 28 of Fig. 2, or the coil 48 of Fig. 1, at one end of these coils and leaving by the other end, thereby setting up a voltage from 30 to 29 of coil 28, or from 35 to 36 of coil 48, due to the IX drop across one-half of either of these coils. Since in Fig. 2 the half of coil 28 between 30 and 29 is connected to the input terminals of the radio receiver, the radio signals picked up by that part of the antenna system 16 other than the lead-in 24 will be impressed on the radio receiver. Likewise in Fig. 1, since the high tension point 38 and mid-tap 36 of coil 34 are connected to the terminals of the radio receiver, the radio signals picked up by the doublet portion of the antenna are impressed on the receiver, the portion of coil 34 between 38 and 35 serving to step up the voltage set up between points 35 and 36. 35

For operation in the broadcast band, or in the latter band and any other adjacent relatively low frequency band, the lead-in and the doublet portion, or antenna proper, are both utilized as pick-up means for radio signal currents. For this purpose mid-tap 29, of coil 28 of Fig. 2 or mid-tap 36 of coil 34 of Fig. 1 may be disconnected from ground as by the opening of switch 39. The entire antenna system 16, including the lead-in portion 24 and the other, or doublet portion, then operates to impress signal voltage across the input terminals 13, 14 of the radio receiver. 40 45

Referring particularly to the operation of the automatic means for shifting between doublet and simple antenna operation as illustrated in Fig. 3, the capacitance means, shown as the condenser 40, is of such capacity that at high radio frequencies, for example 6 megacycles and higher, the reactance of the capacitance between the mid-tap point 36 of coil 48 and ground is so low that this mid-tap point is effectively grounded. The antenna system 16 then operates as hereinbefore described in connection with the operation, on high frequencies and with switch 39 closed, of the system shown in Fig. 1, any man-made noise signals picked up by the lead-in portion 24 being cancelled out. The remainder, or doublet portion of the antenna system operates to impress desired radio signals on the input 60 of the radio receiver. At lower frequencies, however, for example on the broadcast band and also on other relatively long wave bands adjacent the broadcast band, the reactance of the capacitance means represented by the condenser 40 is so much increased that the mid-tap 36 is no longer effectively grounded. The entire antenna system 16 then operates as hereinbefore described in connection with the system of Fig. 1 70 75 on low frequency bands.

It will be seen from the foregoing description of my invention that I have provided an antenna system which may take the form of an antenna unit or kit comprising an antenna preferably incorporating a non-uniform transmission line together with a coupling means, the entire system being adapted to be connected if desired as a unit to the input terminals or input circuits of existing radio receivers, the unit being of such character that highly efficient pick-up of radio signals over wide ranges of high frequency wave bands and desired ranges of low frequency wave bands is insured, the change from doublet operation on high frequencies to simple antenna operation on low frequencies being effected automatically and without complication or added expense.

The antenna in accordance with my invention has been illustrated and described herein mainly in connection with radio receivers. It will be understood, however, that the antenna of the non-uniform transmission line type herein described is applicable to radio transmitters, particularly to radio transmitter use wherein an antenna of good efficiency is required to transmit signals over a relatively wide frequency band without, during operation over any point of this band, reaching the half-wave resonant point.

My invention has been described herein in particular embodiments for purposes of illustration. It is to be understood, however, that the invention is susceptible of various changes and modifications and that by the appended claims I intend to cover any such modifications as fall within the true spirit and scope of my invention.

What I claim as new and desire to secure by Letters Patent of the United States, is:

1. An antenna unit adapted to be connected to a radio receiver of the all-wave type comprising an antenna system including a pair of conductors arranged in converging relation to form a non-uniform transmission line connected at its outer end to a pair of oppositely disposed doublet wires spaced apart a substantial distance in the direction of their lengths, said conductors being connected to a lead-in constituted by a pair of conductors arranged closely adjacent each other throughout their length, said transmission line being of sufficient length to cause the surge impedance of said system to be gradually lowered from a relatively high value at the connection of said line to said doublet wires to a relatively low value at the connection of said line to said lead-in, means to couple said lead-in to said radio receiver, and means connected to said coupling means whereby said antenna system is caused to operate as a doublet system over a high frequency band of radio signals and whereby said antenna system is caused to operate as a simple antenna over a low frequency band of radio signals.

2. In a radio apparatus of the all-wave type, a radio device having input terminals, an antenna of the doublet type for said device adapted to transfer signals with a reduced pick-up of local noise currents, a lead-in connected to said antenna comprising a pair of conductors arranged closely adjacent to each other throughout their length, a coil connected at two spaced points thereof to the lower ends respectively of said conductors, a capacitance means connected between an intermediate point of said coil and the grounded input terminal of said radio device, and means to connect one of said spaced points of said coil to the other of said terminals, said

capacitance means being of such capacity that at relatively high frequencies in operation of said apparatus the reactance of said capacitance means is so low that said intermediate point is effectively electrically connected to said grounded terminals and that at relatively low frequencies said reactance is so high that said intermediate point is effectively electrically disconnected from said grounded terminal.

3. An antenna system for a radio apparatus including two conductors in the outer portion of said system, said conductors being arranged in single doublet form and extending in substantially opposite directions, and means to connect said conductors to said radio apparatus and to cause the surge impedance of said antenna system to be substantially less in the portion thereof adjacent said apparatus than in said outer portion, said means including a gradually converging transmission line having a constant capacity and a gradually varying inductance per unit length, the larger end of said line being connected to the inner extremities of said conductors and the other end of said line being connected through a lead-in to said apparatus.

4. An antenna comprising a pair of oppositely disposed conductors spaced apart in the direction of their lengths, and a non-uniform transmission line including a converging pair of conductors connected respectively to the inner extremities of said first-named pair of conductors, the distance across the open end of said transmission line being of the order of magnitude of the distance between the apex of said converging pair and said open end.

5. An antenna for a radio apparatus comprising a pair of oppositely extending conductors spaced apart in the direction of their lengths, said conductors being connected to a gradually converging transmission line, said line having a constant capacity and a gradually varying inductance per unit length whereby the surge impedance of said transmission line diminishes as said line approaches said radio apparatus, the line bisecting the opening between said converging pair of conductors being vertical.

6. An antenna comprising a pair of oppositely disposed conductors spaced closely adjacent at their inner ends and diverging from said inner ends to form a non-uniform transmission line, and a pair of oppositely disposed doublet wires connected to the open end of said line, the rate of said divergence being relatively rapid and the distance across the open end of the pair being of the same order of magnitude as the distance between said open end and said inner ends, whereby a transfer of radiant energy substantially equal to that in the direction of the line bisecting the opening between said pair of conductors occurs in directions substantially perpendicular to the line of the oppositely disposed doublet wires.

7. In a radio receiver apparatus of the all-wave type, receiver input terminals, an antenna and a lead-in connected thereto comprising a pair of conductors arranged closely adjacent to each other throughout at least a portion of their length, and means to couple said lead-in to said input terminals comprising a step-up autotransformer, said conductors being connected respectively to one extremity of said autotransformer and a point intermediate said extremity and the other extremity of said autotransformer, one of said input terminals being connected to said other extremity, and circuit connecting and disconnecting means between the other of said in-

put terminals and a point of said autotransformer midway between said one extremity and said intermediate point to cause said antenna only to pick up radio signals over a predetermined wave band and to cause both said antenna and said lead-in to pick up radio signals over another predetermined wave band.

8. In combination, an antenna of the doublet type comprising oppositely extending conductors, the ends of said conductors nearer to each other being spaced apart a substantial distance, a pair of conductors, and conductors extending respectively from the opposite conductors of said pair to the inner ends of said oppositely extending conductors, said third-named conductors being spaced apart along their lengths by distances progressively increasing and such that the surge impedance of said third-named conductors at the ends thereof connected to said pair of conductors approximately matches that of said pair

and the surge impedance of said third-named conductors at the ends thereof connected to said oppositely extending conductors approximately matches that of said oppositely extending conductors.

9. In combination, an antenna system comprising an antenna of the doublet type including oppositely extending conductors spaced apart a substantial distance in the direction of their lengths, a pair of conductors, and conductors extending respectively from the opposite conductors of said pair to the inner ends of said oppositely extending conductors, said third-named conductors being spaced apart along their lengths by distances progressively increasing and such that the distance between half-wave resonance points on the reactance curve of said antenna system is substantially increased.

ROBERT B. DOME. 20
